CLAIM

The ornamental design for a vehicle front grille portion, as shown and described.

DESCRIPTION

FIG. 1 is a front view of a vehicle front grille portion according to the present invention.

FIG. 2 is an enlarged front view of the front grille portion shown in FIG. 1.

FIG. 3 is a front left perspective of the vehicle front grille portion shown in FIGS. 1 and 2; and,

FIG. 4 is an enlarged front left perspective view of the front grille portion shown in FIG. 3.

The broken lines in the drawings surround the claimed design, while the ghosted or low contrasted portions are provided to illustrate portions of the vehicle front grille portion that form no part of the claimed design.
